AUTOMATIC SWITCH.

1,286,001.

Specification of Letters Patent. Patented Nov. 26, 1918.

Application filed April 2, 1917. Serial No. 159,371.

To all whom it may concern:

Be it known that we, HENRY A. HOESCHEN and WILLIAM H. HOESCHEN, citizens of the United States, and residents of Omaha, in 5 the county of Douglas and State of Nebraska, have invented certain new and useful Improvements in Automatic Switches, of which the following is a specification.

Our invention relates to electrically actuated switches for controlling an electric motor circuit or the like, wherein it is desired that the circuit be opened and closed automatically, to stop and start the motor or to stop and start the operation of other 10 electrically-operated devices, in accordance with conditions which are varied by the operation of the motor or the like. Thus where an electric motor is employed to operate a compressor for a refrigerant, it may 15 be desirable to stop and start the motor automatically according to decreases and increases of temperature in a refrigerating chamber which is cooled by the compressed refrigerant. The main switch provided by 20 our invention is actuated by electromagnets or solenoids which are energized alternately by electrical energy supplied thereto by the closing of control-circuits, the latter being effected by a thermostat or the like, and the 25 control-circuits being opened alternately by the movement of the main switch, after being closed for a sufficient time to cause operation of the main switch. It is the object of our invention to provide various 30 structural refinements in switches of the class set forth, including an improved form of solenoid adapted to exert a uniform pull upon a core or armature having a relatively long stroke, improved contact-forming 35 means for the main switch by which burning of the contacts by arcing is reduced to a minimum, means for maintaining the control-circuit closed during a maximum proportion of the period of operation of the 40 main switch whereby stopping of the operation at an intermediate or dead position is avoided, and means for locking the main switch both in open and closed positions so that the same is movable only by energization 45 of the appropriate solenoid or electromagnet, effected by the closing of the respective control-circuit.

In the accompanying drawings, Figure 1 is a front view of a switch mechanism embodying our invention, a portion thereof

being in vertical section, and illustrative circuit connections being indicated diagrammatically, Fig. 2 is a vertical section through the axes of the actuating lever and the main switch arms, Figs. 3, 4 and 5 are 60 detail front views showing different positions of the actuating lever relatively to the locking cam-slot, and Fig. 6 is a detail side view of one of the solenoids.

In the illustrated embodiment of our invention, there is provided a suitable supporting plate or switchboard 7, preferably of insulating material and arranged in a vertical position. Near the center of said plate 7 there is an opening through which a 65 stud 8 is passed as shown in Fig. 2, said stud having an integral cylindrical collar 9 in front of the plate and being held in place by a nut 10 screwed on the rear end thereof. The stud has a portion extending in 70 front of the collar, the end of said front portion being threaded and shouldered, and carrying a nut 11 which holds a washer 12 against the shoulder. On the stud between the washer 12 and collar 9 there is pivot- 75 ally mounted a hub 13 having integral upwardly extending arms 14 and 15 and a downwardly extending arm 16. The arms 14 and 15 extend divergently from the hub and near their spaced ends each carries a 80 series of resilient contact-plates 17, which are secured to the arms by screws 19 and insulated therefrom by plates 20, as shown. The end-portions of the contact-plates are 85 curved away from the arms and are adapt- 90 ed to engage the flat faces 21 on the heads of terminal-posts 22, 23, 24 and 25 which are mounted on the plate 7 at the positions shown. The faces 21 on each pair of the terminal-posts are slightly inclined relatively to each other, so that when the contact-plates are moved toward and away from said faces the ends of the plates will engage and disengage serially, the outer 95 plates engaging the faces first and being 100 slightly bent before the next comes into contact with the face. Preferably the outermost contact-plates 18 carry at their ends small blocks 26 of carbon which make the first contact with the faces 21 as the 105 arms 14, 15 move toward the terminal-posts, and also make the final contact with the faces 21 as the arms move away from the terminal-posts. Thus, in breaking the circuits formed through said terminal-posts 110

and contacts, any resulting arcs will be formed between the blocks 26 and the posts, and burning of the plates 17 thereby avoided. The terminal-posts 22, 23, 24 and 25 are connected, respectively, with binding-posts 27, 28, 29 and 30 arranged near the lower edge of the plate 7, the connecting conductors being indicated in Fig. 1 by lines 31. The described parts constitute the main switch mechanism, and the circuit-closing and open-circuit positions thereof are shown by full and dotted lines, respectively, in Fig. 1. It may be noted that at a position intermediate the extreme positions just mentioned, the arms 14 and 15 are symmetrical to a vertical plane through the axis of the pivot-stud 8, so that the weight of the arms tends to cause them to remain in either of the extreme positions to which they are moved.

The solenoids A and B for actuating the main switch are mounted on the plate 7 at opposite sides of the pivot-stud 8. For each solenoid there is an upper angle-plate 32 and a lower angle-plate 33 of which the foot-portions are bolted to the face of the plate 7. Between the horizontal portions of said angle-plates there is a spool consisting of an upper end-plate 34, a tubular sleeve 35 and a lower end-plate 36 through which the sleeve 35 extends to fit within an opening through the lower angle-plate 33. The peripheral portions of the plates 34 and 36 are connected to each other by a plurality of vertical side-bars 37. The solenoid coil 38 is wound on the sleeve 35 between the end-plates, being of course, suitably insulated therefrom. The upper end-plate 34 has a conical projection 39 extending down into the sleeve 35 in spaced relation to the inner surface thereof. A tubular core 40 fits slidably within the sleeve 35, the central opening of the core being slightly larger than the largest diameter of the conical projection 39, so that when the core is raised to its highest position it will not contact with said member 39. The parts 34, 36, 37, 39 and 40 are of soft iron, and the sleeve 35 if of non-magnetic material such as brass. When the solenoid is energized by a suitable current passing through the coil 38, the core 40 is drawn upwardly with a comparatively uniform force, owing to the provision of the conical member 39 by which the air-gap of the magnetic circuit is reduced to a minimum and magnetic leakage avoided.

To the lower ends of the solenoid cores 40 are pivotally connected the upper ends of links 41, and the lower ends of said links are pivotally connected with the lateral arms 42 of a rocking-lever which is pivotally mounted on a stud 43 secured to the plate 7 near the lower edge thereof, the axis of said stud being in the vertical plane of the axis of

the pivot-stud 8. Alternate energization of the solenoids moves the rocking-lever between the position shown by full and dotted lines in Fig. 1. The rocking-lever has an upwardly extending arm 44 of which the upper end is 70 forked and straddles an extended portion 45 of the arm 16. In said part 45 there is a cam-slot consisting of two similar curvilinear portions symmetrically arranged with respect to the center of the arm 16, the said 75 slot-portions having concave outer sides *a* and convex inner sides *b*. The ends of the cam-slot are more distant from the axis of the stud 8 than the central or intermediate portion of the slot, and the longitudinal center-line of the slot is a slightly modified epicyclodal curve generated upon a circle concentric with said stud 8. A small roller 46 fits within the cam-slot, said roller being revoluble upon a pin 47 extending between 80 the forked ends of the arm 44. When the rocking-lever is tilted to either of the extreme positions shown by full and dotted lines in Fig. 1, the roller 46 rests in an end of the cam-slot, which thus forms a stop for 85 limiting movement of the rocking-lever. As the rocking-lever is moved from a position such as shown in Fig. 3 toward a position such as shown in Fig. 4, the roller first 90 presses upwardly against the side *a* of the slot, and tends to tilt the switch-arms 14, 15 slightly farther in the direction of the arrows *c* in Fig. 3. As the movement of the rocking-lever continues, the roller presses against the side *b* of the slot as shown in 95 Fig. 4, moving the switch-arms in the direction of the arrow *d* in said figure, and after passing the intermediate position shown in Fig. 5 the roller presses against the other side *a* of the slot so that the movement, of 100 the switch-arms is continued in the direction of the arrow *d* until the roller has almost reached the end of the slot opposite that from which its movement started. It will be seen that when the roller is in either 110 end of the cam-slot, the switch-arms are, in effect, locked in position, since a force applied to the switch-arms and tending to move them in either direction will be resisted by the roller, which can only be 115 moved by the tilting of the rocking-lever. It may be noted also that the pivotal center of the rocking-lever is at its lowermost part, so that the weight of the lever tends to keep it in either of the two extreme positions to 120 which it may be moved.

On the rear side of the rocking-lever arm 44 there is secured a block 48 of insulating material, and to the rearward side of said block there is secured a plate having a resilient upper and lower-end-portions 49 and 50 which extend angularly toward the face of the switchboard 7, as shown in Fig. 2. Said resilient end-portions form sliding contacts or brushes for engagement with 130

arcuate contact-plates 51, 52 and 53 secured on the face of the switchboard, the lower brush 50 constantly engaging the plate 51, and the upper brush 49 having portions engageable with both of the plates 52 and 53. Each of the arcuate contact-plates is disposed concentrically with the pivot-stud 48 of the rocking-lever, and the upper plates 52 and 53 are so arranged that the brush 49 will disengage therefrom, respectively, near the termination of the movements of the rocking-lever caused by energization of the solenoids A and B. The plates 52 and 53 are connected by wires 54 and 55 with the respective solenoids A and B, the other terminals of the solenoids being connected by wires 56 and 57 with binding-posts 58 and 59 near the lower edge of the switchboard 7. A binding-post 60 is connected by wires 61 with the lower contact-plate 51.

Referring now to the illustrative circuit-diagram at the lower part of Fig. 1, there is indicated a three-phase alternating-current motor 62 which receives electrical energy from supply-mains 63, 64 and 65 connected through a manually-controlled switch 66. The branch 64 of the motor-circuit is extended directly from the switch 66 to the motor, the branch 63 is connected with the binding-posts or terminals 27 and 28 of the automatic switch, and the third branch 65 is connected with the binding-posts 29 and 30. A thermostatic device is indicated, having a movable central member 67, a fixed contact 68 which is engageable by the member 67 when the temperature reaches a determined maximum, and a fixed contact 69 with which the member 67 is engageable when the temperature reaches a determined minimum. The contact 68 is connected with the binding-post 58 and the contact 69 is connected with the binding-post 59, while the energy for the thermostat-and-solenoid circuits is derived from the mains 63 and 65, which are connected respectively with the binding-post 60 and the central member 67 of the thermostat by wires 70 and 71. It will be seen that when the automatic main switch is in the closed position shown by the full lines in Fig. 1, a circuit through the solenoid B may be closed by movement of the thermostat-member 67 into engagement with the contact 69. Upon energization of said solenoid B the rocking-lever and switch will be moved to the open position shown by dotted lines in Fig. 1, and near the end of such movement the brush 49 will disengage from the contact-plate 53, thereby opening the circuit through the solenoid B. If then the thermostat-member 67 moves to engagement with the contact 68 a circuit will be thereby closed through the solenoid A, causing the switch to be returned to the closed position, and near the end of the closing movement the brush 49 will be disengaged

from the contact-plate 52 to open the circuit through said solenoid A. It should be particularly noted that the opening of each of the solenoid-circuits occurs only after the movement of the rocking-lever caused by energization of the respective solenoid is nearly completed, the brush 49 remaining in contact with both plates 52 and 53 except at the extreme positions of the rocking lever. Thus there is no possibility of the switch-mechanism stopping at an intermediate position, as there is not only the momentum of the parts to complete the movement after the breaking of the solenoid-circuit, but also a certain continued pull from the solenoid itself, due to the fact that its energization is not lost instantaneously upon the opening of the circuit. Due to the proportionally large part of the operating period during which the solenoid-circuits remain closed, smaller solenoids may be used, and less energizing current, than in switches of this general character wherein the circuit of the actuating solenoid or electromagnet is broken at or near the beginning of the movement of the switch. The smaller operating current required for the solenoids, makes it possible to control the same directly from a fairly delicate thermostatic device without danger of injuring or destroying the thermostat contacts, while the contacts of the main switch may be of such proportions as to control effectively a very heavy current in the motor-circuit or the like.

Now, having described our invention, what we claim and desire to secure by Letters Patent is:

1. In an automatic electric switch, a pivoted main switch member having a cam-slotted arm, a pivoted controlling-lever, a part carried by said controlling-lever and entering the cam-slot in said arm of the main switch member, means for actuating said controlling-lever in alternating directions to move the part toward opposite ends of the cam-slot and simultaneously actuate the main switch member, the ends of said cam-slot forming abutments to limit movement of the controlling-lever, and the sides of said cam-slot adjoining the ends thereof adapted to engage said part to prevent movement of the main switch member when said part is seated in either end of the cam-slot.

2. In an automatic electric switch, a pivoted main switch member, an oscillating controlling member pivoted on an axis parallel with that of said switch member, there being in the switch member a cam-slot having symmetrical end-portions curved divergently from a central portion adjacent to the pivotal axis of the switch member, the controlling member having a part entering said cam-slot and engageable with the sides thereof to actuate the switch member about its axis while traversing the intermediate por-

- tion of the slot and to hold the switch member substantially stationary when traversing the terminal portions of the slot, and means for actuating said controlling member, said actuating means being partially controlled by said member, whereby the actuating force acting thereon is discontinued only when the part in the cam-slot is traversing the terminal portions of the slot.
3. A structure as specified in claim 2, in which the actuating means for the controlling member comprise a pair of electromagnets and energizing circuits therefor, and switches in said circuits having elements carried by the controlling member, said switch
- elements opening the circuits during movement of the controlling member subsequent to the phases of movement during which the main switch member is actuated.
4. A structure as specified in claim 2, in which the controlling member is gravity-biased to positions at which the part in the cam-slot lies in the terminal portions of said slot, whereby said controlling member after passing an intermediate position of unstable equilibrium tends to move on to the respective extreme position thereof.
